United States Patent Office

Des. 223,210

Patented Mar. 28, 1972

223,210

PLATE OR SIMILAR ARTICLE

Edward J. Bennett, Weston, Conn., and Ronald M. Johnson, New York, N.Y., assignors to Owens-Illinois, Inc.

Filed Nov. 20, 1967, Ser. No. 9,463

Term of patent 14 years

Int. Cl. D7—01

U.S. Cl. D44—15

The figure is a plan view of a plate or similar article showing our new design and a repeat portion being shown between dotted lines. The plate is of a conventional configuration when viewed from the side and bottom thereof.

We claim:

The ornamental design for a plate or similar article, substantially as shown and described.
